UNITED STATES PATENT OFFICE

EDWARD F. FORSGARD, OF WACO, TEXAS, ASSIGNOR OF ONE-THIRD TO JAMES W. BASS
AND ONE-THIRD TO FRITZ BRAATZ, BOTH OF WACO, TEXAS.

PACKAGE-TIE.

1,132,571.

Specification of Letters Patent. Patented Mar. 23, 1915.

Application filed December 1, 1913. Serial No. 803,942.

To all whom it may concern:

Be it known that I, EDWARD F. FORSGARD, a citizen of the United States, and a resident of Waco, in the county of McLennan 5 and State of Texas, have made certain new and useful Improvements in Package-Ties, of which the following is a specification.

This invention relates to package ties, and one of the principal objects thereof, is to 10 provide a tie with which the ends of a string that has been passed around a package may be securely held, without cutting or abrading the string, which would necessarily weaken the same.

15 Another object of the invention is to provide a package tie which is simple in construction, durable, efficient in operation, and inexpensive to manufacture.

With these and other objects in view, 20 which will become apparent as the description proceeds, the invention resides in the construction, combination and arrangement of parts hereinafter more fully described and claimed and illustrated in the accompanying drawing, in which like characters of reference indicate like parts throughout the 25 figures, of which—

Figure 1 represents a perspective view of a package showing the tie in use thereon, 30 the ends of the string binding the package being loose. Fig. 2 represents a top plan view of the tie showing the manner in which the string or cord is arranged thereon. Fig. 3 represents a side elevational view of the package tie, Fig. 4 represents a 35 central horizontal sectional view therethrough, Fig. 5 represents an elevational view looking toward the larger end of the tie, and Fig. 6 represents a view similar to Fig. 2 showing the manner in which the 40 ends of the string will be disposed when the same are sealed. Fig. 7 represents a perspective view of a modified form of the tie.

Referring more particularly to the drawing, 45 the tie comprises a substantially rectangular plate or body 5 whose ends are turned over in spaced relation to the plate to form flanges 6, the inner edges of the flanges lying in spaced and parallel relation with each 50 other, and in spaced relation with the plate, the outer edges of the flanges converging from the larger end 7 of the tie to the smaller end 8 thereof.

The tie is provided at the junction of 55 flanges 6 and plate 5, with oppositely dis-

posed substantially wedge shaped recesses 9, which extend from opposite ends of the tie toward the central portion thereof, and the top and bottom surfaces 10 of the wedge shaped recesses 9 converge toward the center of the tie as shown in Fig. 5. The inner ends of the recesses are gradually tapered off as at 11 to merge with the outer edges of the tie, thus forming at the inner end of each recess a substantially sharp jaw 65 or grip 12 adapted to engage a cord, which may be inserted in the recess and which will become gradually clamped as it nears the inner end of the recess, but the jaw 12 is slightly rounded so as not to cut the cord. 70

In utilizing the tie, one end 13 of a cord 75 may be passed through one of the recesses 9 and clamped in the inner end thereof, as shown in Fig. 2, and the cord may then be passed in the general direction of the tie 80 from the larger toward the smaller end thereof, around the package to be tied, extended through the tie as at 14 between one of the flanges and the body, alongside the portion of the cord near end 13, and extended out between the flange and the body 85 at the smaller end of the tie as at 15, around the package at right angles to the first direction, and the opposite end 16 may be passed between the opposite flange 6 and the body 90 portion, from the larger end of the tie, and through the opposite recess, as shown at 17, and clamped into the end of the last said recess, whereby the cord will be securely held in place on the package. 95

The ends of the string may be left loose as shown in Figs. 1 and 2, and would not be liable to become disengaged from the tie except by intention, but in order to prevent the undoing of the string except by authorized persons, or to give evidence to the fact should the package be undone by unauthorized persons, the ends of the cord may be sealed as illustrated in Fig. 6, and in doing so, the end 16 may be laid along the surface 100 of the package and the end 13 then bent up and over its adjacent flange 6, and under the opposite flange through the opposite recesses, and alongside end 16, whereupon the ends can be sealed to the package as shown. 105

It is evident by my construction that any cord engaged in one of the recesses will be securely clamped therein as it nears the inner end thereof, and will be engaged by the jaw 12 and effectually prevented from acci- 110

dental slipping out of the recess. In securing the string in place in the tie, various portions of the string during this operation will be passed between the inner edges of 5 the overhanging flanges 6, and for this reason the ends of the flanges have been rounded as at 18 to prevent cutting or abrading of the string.

In the form shown in Fig. 7, one of the 10 recesses 9 terminates in an opening or eye 19 through which may be threaded one end of the cord, and the cord may then be knotted to prevent accidental displacement or 15 loss of the cord from the tie. In threading the eye, the cord may be passed directly through the same or may be slipped through the recess 9 into the eye.

Although I have described the preferred embodiment of my invention, I may desire 20 to make such changes in its construction, combination and arrangement of parts as do not depart from the spirit of the invention and the scope of the appended claims.

I claim:

25 1. A package tie comprising a flat body portion having its opposite ends bent over the body portion in spaced relation thereto and to each other, the meeting portions of the ends with the body provided with oppositely disposed substantially wedge-shaped recesses terminating in gripping jaws, said recesses extending from opposite ends of the tie toward the center thereof, the edges of 30 the recesses converging inwardly toward

the center of the tie, the recesses being tapered from the gripping jaws to the surface of the tie. 35

2. A package tie comprising a plate having flanges spaced therefrom, said tie provided at the meeting points of the plate and 40 flanges with recesses, said recesses having their edges longitudinally converging and transversely converging, and a binding element, means for engaging said binding element at the inner end of one of the recesses, 45 said binding element adapted to be passed around a package, and means at the inner end of the opposite recess for engaging the binding element.

3. A package tie providing a plate having flanges spaced therefrom, and provided with oppositely disposed recesses, the edges of each recess converging longitudinally and transversely, the tie being cut away at the inner end of each recess to form a substantially sharp gripping jaw directed toward 55 said recess.

4. A package tie provided with recesses, said tie being beveled from its outer surfaces adjacent the recesses toward said recesses at the inner ends thereof to form gripping elements directed toward the recesses. 60

EDWARD F. FORSGARD.
